UNITED STATES PATENT OFFICE.

JOHN ERICKSON, OF CHICAGO, ILLINOIS, ASSIGNOR, BY MESNE ASSIGNMENTS, TO FIRST TRUST AND SAVINGS BANK, TRUSTEE, OF CHICAGO, ILLINOIS.

ELECTRICAL-IMPULSE-TRANSMITTING DEVICE.

No. 909,383.

Specification of Letters Patent.

Patented Jan. 12, 1909.

Application filed August 20, 1906, Serial No. 331,302. Renewed October 14, 1908. Serial No. 457,751.

To all whom it may concern:

Be it known that I, JOHN ERICKSON, a citizen of the United States of America, and resident of Chicago, Cook county, Illinois, have invented a certain new and useful Improvement in Electrical-Impulse-Transmitting Devices, of which the following is a specification.

My invention contemplates a device of the character and for the same general purpose as that described in my copending application Serial No. 331,304, filed August 20th, 1906. This application is, therefore, subordinate to said other application.

My present invention contemplates a device for preventing the rotatable dial or apertured disk of a subscriber's automatic telephone from being manually forced back to its normal position, and of a different form from that disclosed in my said other application.

My present invention, as herein disclosed, contemplates a device for positively locking the dial against back rotation as soon as it reaches the limit of its forward rotation, making it necessary to release the dial in order to unlock the same. The dial cannot move at all until the calling subscriber lets go of the same, as will hereinafter more fully appear.

In the accompanying drawings Figure 1 is a front elevation of a subscriber's automatic telephone having a rotatable dial or calling disk embodying the principles of my invention, certain portions thereof being broken away for convenience of illustration. Fig. 2 shows the mechanism of the dial and front of the casing removed. Fig. 3 is a rear elevation of the mechanism. Fig. 4 is a sectional view showing the toothed wheel or member by which the springs are pressed for transmitting the impulses. Figs. 5 to 10, inclusive, show different positions of the springs and the said toothed wheel, and show how the impulses are transmitted, in the well-known manner.

As thus illustrated the dial A is of the usual and well known form, being positioned at the front of the telephone casing. B. The shaft or arbor C supports the said dial and operates the impulse-transmitting mechanism within the telephone casing. It will also be understood that a spring is em-

ployed for returning the dial to its normal position. This dial is apertured near its outer edge, as shown, so as to enable the subscriber to rotate it in the usual and well known manner. Said apertures are preferably ten in number, whereby the subscriber may partially rotate the disk or dial in accordance with each digit of any called telephone number. Within the telephone casing there is a ring or circular flange D which is suitably connected with the shaft or arbor C, or directly with the said rotatable dial or disk A. This ring or circular flange D is provided with peripheral apertures d, there being one aperture for each opening in the dial or disk, as indicated in Fig. 1.

To the under side and a little to the left of the telephone casing is an inclosure E containing a pivot stop F, which latter is of the usual and well-known character, except for the fact that it has its lower end pivoted at f and provided with an arm f¹. A locking arm G is also pivoted at f and provided with an end portion g adapted to rise up back of the dial end engage any one of the apertures d in the circular flange D.

It will be understood that spring means are provided for connecting the stop F with the arm G, whereby the two are capable of relative movement, the spring being so applied that it tends to keep the two normally in the position shown in Fig. 1. A spring H is secured to the inclosure E and adapted to bear upon the arm f¹, thus keeping the upper end of the arm G in its normal or resting position upon the pin g¹. The dial is rotated in the usual and well-known manner by inserting a finger in one of the openings a, and its forward rotation is limited by the striking of the finger against the stop F, the movement continuing until this stop is in the position indicated by dotted lines in Fig. 1. When the movement of the dial is thus arrested, it will be seen that the end portion g of the arm G is thereby thrown into engagement with one of the apertures d, thus positively locking the dial against rotation in either direction—that is to say, so long as the finger continues to hold the stop F in its upright position. As soon as the calling subscriber releases the dial, however, the stop F then snaps back into its normal po-

sition, causing the arm G to also assume its normal position, thus releasing the dial and allowing its spring to carry it back to normal position. It will be understood, of course, that it is during this back rotation of the dial that the electrical impulses are transmitted over the subscribers' line for the purpose of performing the desired switching operation at the exchange or central station.

10 This, however, is all fully set forth in my application above referred to, and is a thing well understood. With this arrangement the dial cannot be forced back to its normal position, as it remains locked against 15 movement as long as the subscriber retains his finger in engagement with the opening in the dial. In other words, while the finger is still in engagement with the opening in the dial the mention of the latter cannot be 20 reversed, for the reason that considerable backward movement is necessary on the part of the stop F in order to carry the end portion *g* out of engagement with the aperture *d* in the flange D, and before the dial is thus 25 unlocked. With this construction the calling subscriber will be reminded of the proper way in which the dial must be operated should he attempt to force the dial back to its normal position instead of releasing it 30 and allowing it to travel back in the right manner. He will then, of course, instantly remove his finger from the opening in the dial, and thus permit the impulse-transmitting operation to proceed in the desired 35 manner. Without this arrangement, and as explained in my said other application, more or less trouble might result from a forcing or accelerating of the back rotation of the dial.

40 Figs. 2 to 10, inclusive, illustrate the well-known form of subscriber's calling mechanism, in connection with which I have elected to describe my invention. Referring to Fig. 4, it will be seen that the impulse wheel I is mounted on the shaft C, and is adapted to 45 operate the impulse springs J and K relatively to the ground post L, in the well-known manner. Referring to Fig. 2 it will be seen that the spring M operates like a clock spring, and serves to give the impulse 50 wheel and dial a backward rotation. As this mechanism forms no part of my present invention, no further description is necessary.

55 From the foregoing it will be seen that I provide a pivoted finger stop adapted to engage the calling subscriber's finger to limit the forward rotation of the dial—that is to say, to limit its rotation for any given digit of the called number. It will also be seen 60 that I provide an automatic locking device which is operated by the said pivoted finger stop, and which serves to positively lock the dial against back rotation after reaching the limit of its forward rotation. As shown,

the dial has an additional aperture for long distance calling.

It will be seen that the dial lock or retarding device is operative to oppose or prevent forcing or undue acceleration of the dial, but is inoperative to oppose or retard the 70 propelling power of the spring by which the impulse wheel and dial are returned to their normal positions. Furthermore, it will be seen that the dial lock thus provided is adapted to unlock the dial as soon as the 75 latter is released by the subscriber—that is to say, as soon as the subscriber withdraws his hand from the dial. In this way the lock does not hold the dial and impulse wheel against rotation for any time whatever after 80 the subscriber lets go of the dial. Furthermore, it will be seen that the locking of the dial is accomplished by the pressure of the finger as the dial approaches the end of its forward rotation, the dial being unlocked 85 as soon as the finger is withdrawn from the hole in the dial.

What I claim as my invention is:—

1. In automatic telephony, the combination of a rotatable calling dial, spring means 90 for rotating the dial back to its normal position, a stop for limiting the forward rotation of the dial, and a locking device for locking the dial against back rotation as soon as the said stop is engaged by the calling subscriber's finger.

2. In automatic telephony, the combination of a rotatable calling dial, spring means for returning the dial to its normal position, means for limiting the forward rotation of 100 the dial, and automatic means for positively locking the dial against back rotation as soon as it reaches the limit of its forward rotation.

3. In automatic telephony, a rotatable calling dial provided with means for restoring it to normal position, and provided also with automatic means for positively locking it against back rotation after reaching the limit of its forward rotation, adapted to 110 release the dial as soon as the subscriber releases the same.

4. In automatic telephony, the combination of a rotatable calling dial, a pivoted stop for limiting the forward rotation of the 115 dial, an apertured flange rotatable with the dial, a locking arm adapted to engage the apertures in said flange, means by which the locking arm is operated by the said stop, and spring means for holding the stop and locking arm in their normal positions, for the purpose set forth.

5. In automatic telephony, the combination of a rotatable apertured calling dial, a pivoted finger stop for limiting the forward 125 rotation of the dial, and means operated by the said stop for positively locking the dial against back rotation.

6. In a telephone system, a calling dial, and means operated by engagement with the subscriber's hand for locking the dial at the end of its forward rotation, but adapted to unlock the dial as soon as the subscriber releases the same.

7. In a telephone system, a rotatable calling dial, means automatically operated in the forward rotation of the dial for locking

the same against backward rotation, but adapted to unlock the dial as soon as the subscriber releases the same.

Signed by me at Chicago, Cook county, Illinois, this 17th day of August, 1906.

JOHN ERICKSON.
